ADJUSTABLE WRENCH

James E. Fercana, Youngstown, Ohio

Application June 20, 1956, Serial No. 41,988

Term of patent 14 years

(Cl. D54—16)

Figure 1 is a perspective view showing one side and the bottom of the adjustable wrench, embodying my new design.

Figure 2 is a perspective view showing the top and the other side thereof with the jaws in closed position.

The characteristic feature of my design for the wrench disclosed resides in the handle member having the configuration shown.

I claim:

The ornamental design for an adjustable wrench, as shown and described.
